FOUNDATION TEMPLET FOR BUILDINGS

**Roy William Rumble, Pretoria, Transvaal,
Union of South Africa**

**Application February 14, 1945, Serial No. 577,898
In the Union of South Africa March 9, 1944**

13 Claims. (Cl. 25—131)

This invention relates to templets adapted to be laid out on the ground or, for instance, on a fundation slab, to define the plan of a building that is about to be erected. In some cases the templet defines the position of, and may form part of, shuttering for moulding concrete walls. In other cases it defines and may form part of, the wall itself; particularly when the latter is a hollow wall of a portable building composed of panels connected and supported edgewise.

A templet according to the invention consists of an assembly of manufactured units adapted to be assembled in various combinations to accord with the shape and size of the walls of the building. The assembly comprises continuity structure, essential units of which are corner units consisting of two arms rigidly extending from one another at right angles, or such other angles as the building may require. There are two types of corner units, one type in which the visible surfaces of the walls to be erected form a hollow or exterior angle of less than 180° which in the following specification and claims I designate as "re-entrant" and the other type in which the visible surfaces form a protruding or exterior angle of more than 180° and which I designate as "salient" in accordance with the use with polygons. In the case of corner units for re-entrant angles, a gusset or the like is provided for making the angle rigid. The templet further includes structure that, in the assembly, defines the straight walls between pairs of corners and joins the corner units in a circuit which is usually a closed circuit. Said continuity structure thus includes the arms of the corner units and also includes separate straight bars that come between two such arms in line. There are also coupling units for joining the parts composing the continuity structure and ranging said parts in straight lines. The coupling and corner units and the straight bars are so formed that the coupling units are capable of being engaged with both corner units and straight bars against relative lateral movement whilst being relatively movable longitudinally, and remaining thus engaged, to vary the dimensions of the assembly.

According to a feature of the invention, the templet comprises at least two templet sets, one of which defines an inner element of a double wall or the inner surface of a wall and another of which defines the outer element of the same double wall or the outer surface of the same wall. Said templet sets are connected by transverse ties that are preformed to engage at their ends with

2
said templet sets and space the latter properly apart from one another.

According to a further feature of the invention, the templet is incorporated in and forms the footing of walls erected on it. Said walls may be formed of panels having edge formations constructed to engage edgewise with similar panels and other parts of walls; and the templet is formed with an upward edge or surface that interengages or interlocks with the lower edge formations of panels or wall units laid on it. Said interengaging formations are usually of the general tongue-and-groove type.

The means whereby the abovementioned ties engage with the respective templet sets is prefer-

15. engage with the respective templet sets is preferably such that upon laying the ties with their ends properly positioned on the templet, the superimposition of the wall panels on the templet automatically secures the ties to the templet with
20. the inner and outer sets of the latter properly spaced apart and tied together by the ties. With this object the ends of the ties are shaped in cross section to engage with the aforesaid inter-engaging or interlocking edge or surface formations.
- 25.

The invention is illustrated in the accompanying drawings in which:

Figure I is a plan view of a templet for a two-roomed building.

Figure II is a perspective view illustrating the use of the templet.

Figure III is an enlarged cross section through a bar 6 and coupling 7.

The templet shown in both Figures I and II and indicated generally by 2, defines the plan shape of two parallel sets of walls, which may be for instance the two elements of the hollow wall of a portable building, or the inner and outer shuttering walls temporarily set up to mould a concrete wall between them. There are accordingly at least two templet sets viz. an outer set indicated by letter A and an inner set indicated by letter B. Each room of the building has its own inner templet set; the second inner templet set in the illustrated example being indicated by B¹. Each templet set forms a closed circuit.

50 Each templet set comprises corner units indicated by the numeral 3 and consisting of two arms 4 rigidly fixed to one another at right angles—or in some other angular relationship in the unusual case of a building that is not rectangular. The corner units of the inner set B or B¹ are principally for defining re-entrant corners between the walls. Such re-entrant corner units 55 are indicated by 3^b, and their arms 4 are made

highly rigid with one another by a gusset or diagonal tie 5 between them. The corner units of the outer set A are principally for salient angles; such salient angle corner units, indicated by 3^a are not usually provided with a special stiffening formation.

Each templet set also includes straight bar units 6 and coupling units 7 which connect the arms 4 of the corner units to the bars 6 and the bars 6 to one another. Said coupling units 7 are shown as sleeves or profiled fish plates that fit friction-tight and telescopically on the adjacent ends of the arms 4 and of the bars 6 and are long enough to hold said parts firmly in line across the joints between them.

The whole of the continuity structure, which includes the arms 4 of the corner units and the separate bars 6, is formed of sheet metal pressed to a common cross sectional shape which imparts longitudinal stiffness and provides a base that stands stably on a flat surface. The section shown enlarged in Figure III includes that of an upwardly directed tongue 8 of a tongue-and-groove connection, the ends 9, 9 of which provide the stable base. The coupling units 7 are also made of sheet metal pressed to a cross sectional form that enables them to connect the arms 4 and bars 6 telescopically; and if the bar and arm section is of a form—described later—that is suitable, the units 7 are made of the same section as the bars and arms. In using the term "the same section" it is assumed that the sheet metal is sufficiently thin relatively to the dimensions of the section for there to be no significant difference between the internal and the external profiles of the section.

When the templet comprises two or more templet sets, it also includes ties 10, the function of which is to connect the similar elements of the sets and to hold said similar elements parallel with one another and properly spaced apart according to the overall thickness of the building walls to be formed. The ties here shown are similar to those disclosed in Union of South Africa patent specification No. 1,121 of 1943. They consist of flat strips of sheet metal having end portions 11 bent to form a tongue section that is transverse to the length of the tie, and that fits the tongue 8. The length of the ties corresponds to the intended overall thickness of the wall to be formed; and may vary accordingly as the wall is an outer wall or a partition wall.

In order to make use of the templet in the preferred manner, a level foundation surface 12 (Figures I and II) is prepared, by for instance building a concrete foundation 13 for the building. It is convenient to assemble one of the templet sets first; say set B. To do this a corner unit 3^a is laid down and a bar 6 is attached to each of its arms 4 by the couplings 7. Other bars are similarly jointed on as may be necessary; the couplings keeping the bars and arms aligned at their joints. A corner element is added at the end of each line thus formed; the telescopic character of the joints enabling said lines to be adjusted to length with precision. The process is continued until the circuit of the set B is completed. The set B¹ is similarly completed; and the parallel elements m and n of the two sets B, B¹ are connected by several ties 10. These ties are laid transversely to the continuity structure and with their end portions 11 engaged, either under or over the bars 6 and arms 4 and so that their tongue shapes nest into the tongue shapes of said bars and arms.

The inner sets B and B¹ having been thus as-

sembled, more ties 10 are engaged with said sets at intervals and directed outwardly. The outer set A is now assembled in the same way as the inner sets and in addition so as to engage with the outer ends of the last mentioned ties. Since the inner ends of the ties are already engaged with the inner sets, the mere engagement of the outer set units with the outer ends of the ties causes said outer set to be positioned parallel with and properly spaced from the inner sets, without further measurement.

The corner units and especially the gusseted corner units 3^b are important in determining the squareness of the layout; and if some lack of squareness has appeared during the assembly, shaking the assembled templet, by enabling elastically bent parts to straighten out, will usually ensure complete squareness all through the layout.

The templet thus assembled may be employed in various ways to impart its form to the walls of the intended building. The lower course of blocks of a concrete block wall, for instance, may be correctly laid out by setting said blocks in the space between the inner and outer templet sets. In such an instance, the templet may be disassembled and removed piecemeal as soon as said lower course has been laid.

However the templet shown is specially adapted to form a footing which is incorporated in the walls of which it defines the plan. It is particularly adapted to form the footing for walls of the kind described in Union of South Africa patent applications Nos. 1,120, 1,120A and 1,121 of 1943 and consisting principally of panels that interengage edgewise. Said panels are indicated in Figure II by 14. Their lower edges are shaped as a tongue-and-groove formation complementary to that of the arms 4 and bars 6; and in the example shown as a somewhat V-shaped groove. The upper edges of the panels are also of tongue and groove formation; and said upper edges of the two wall elements are tied and spaced by ties indicated by 15. The drawing also shows waling members 16 interposed between the panel courses as described in patent application No. 1,120 of 1943; and it is pointed out that the templet arms 4 and bars 6 perform a function similar to that of said waling members in keeping the lower edges of horizontally adjacent panels in alignment. The panels 14, in turn, duplicate the aligning function of the coupling members 7, where the former cross the joints of the bars 6 and arms 4.

The two parallel walls X and Y thus formed by the panels may, as mentioned above, be the two elements of a hollow wall in which the templet and the ties remain as permanent features. Equally well they may be the inner and outer walls of shuttering between which a concrete wall is moulded as suggested at 17. In that case, the panels 14 and the parts of the templet are disassembled after the wall 17 is formed and can be reassembled an indefinite number of times. The ties 10 and 15 remain embedded in the concrete.

In order to make the section of the arms 4, the bars 6 and the coupling 7 one that is telescopic in the sense of the outer one of a coupled pair of such members embracing the inner one, at least as long as the sections are not purposely rotated relatively to one another, there is added to the tongue section already described, the further section element consisting of the straight limb 18 extending upward from one side of the general V section and hooked over at 19 at its upper end towards such V section; but this specific form is not claimed in this application. The limb 18, 19 is

provided at the outer edges of the arms 4; and the bars 6 are so arranged when assembled that said limb is also at their outer sides, as appears from the drawings. This allows the moulding faces 20 of the panels 14, when the latter are shuttering panels, to extend practically down to the foundation face 12; being separated therefrom only by the thin edges 21 of the templet sections.

I claim:

1. A foundation templet suitable for laying out on a foundation surface to define the plan of a building to be erected, comprising an assembly of manufactured units adapted to be assembled in various combinations in accordance with the thickness and length of the walls of the building and their positional relationship with one another, said assembly comprising continuity structure including corner units consisting of two arms rigid with one another in the angular relationship of the corners of the building, straight bars between the arms of two corner units, said bars and arms being formed of sheet material bent to cross sectional form affording longitudinal stiffness, the cross section of the arms being the same as that of the bars and being such as to rest stably on a flat surface, the templet also comprising coupling units that connect the aligned ends of said bars with one another and with the aligned ends of said arms, the said coupling units so formed as to be capable of being engaged with both corner or straight units against relative lateral movement whilst being relatively movable longitudinally and remaining thus engaged, to vary the dimensions of the assembly.

2. The templet claimed in claim 1, the sheet material of which is sufficiently thin not significantly to affect the cross sectional shape.

3. The templet claimed in claim 1, in which the coupling units are of the same cross section as the arms and bars; and in which said cross section is such that an outer member encloses an inner member of the same section.

4. The templet claimed in claim 1 providing an upward edge adapted for the connection thereto of the edges of wall panels constructed for edgewise connection with other parts of a wall structure thereby to support as a footing, without lateral scaffolding, said wall of panels.

5. The templet claimed in claim 1 providing an upward edge of general tongue-and-groove cross-section adapted to engage with the complementally formed edges of wall panels, and to support the wall of panels as a footing.

6. The templet claimed in claim 1 in which said units are formed of bars of sheet material of general V cross-sectional shape with the point of the V directed upwardly and the ends of the V arms resting on the ground.

7. A foundation templet suitable for laying out on a foundation surface to define the plan of a building to be erected, comprising several templet sets including inner and outer sets, and a number of ties connecting said sets and spacing them apart according to the thickness of the intended walls; each of said sets comprising an assembly of manufactured units adapted to be assembled

in various combinations in accordance with the thickness and length of the walls of the building and their positional relationship with one another, said assembly comprising continuity structure including corner units consisting of two arms rigid with one another in the angular relationship of the corners of the building, and straight units joining a series of corner units and defining straight walls between said corners, and coupling

10 units that connect the aligned ends of said arms and straight units; the coupling, corner and straight units being so formed that the coupling units engage with both the straight and corner units against relative lateral movement whilst 15 being relatively movable longitudinally, and remaining thus engaged, to vary the dimensions of the assembly; the said continuity structure being shaped to act as a footing for a panel wall.

8. The templet claimed in claim 7, in which the 20 ends of the ties are formed to engage with the cross sectional forms of the respective templet sets and thereby determine the spacing apart of the sets.

9. A foundation templet as claimed in claim 7, 25 in which the outer and inner templet sets form the footings of removable shuttering walls for moulding a permanent wall between them.

10. The templet claimed in claim 7 providing 30 an upward edge adapted for the connection thereto of the edges of wall panels constructed for edgewise connection with other parts of a wall structure, thereby to support as a footing, without lateral scaffolding, said wall of panels.

11. The templet claimed in claim 7, providing 35 an upward edge adapted for the connection thereto of the edges of wall panels constructed for edgewise connection with other parts of a wall structure, thereby to support as a footing, without lateral scaffolding, said wall of panels; the 40 said upward edge being of general tongue-and-groove cross sectional form.

12. The templet claimed in claim 7 in which 45 the said units are formed of bars of sheet material of general V cross-sectional shape with the point of the V directed upwardly and the ends of the V resting on the ground.

13. The foundation templet claimed in claim 7 in which the said units are formed of bars of sheet material of general V cross-sectional shape 50 with the point of the V directed upwardly and the ends of the V resting on the ground, and in which the ties are complementally formed towards their ends to engage with said units.
